UNITED STATES PATENT OFFICE.

HENRY C. SMITH, OF NEW YORK, N. Y.

WINDOW.

No. 805,387.

Specification of Letters Patent.

Patented Nov. 21, 1905.

Application filed July 3, 1903. Serial No. 164,252.

To all whom it may concern:

Be it known that I, HENRY C. SMITH, a citizen of the United States, residing in New York, in the county of New York and State of New York, have invented certain new and useful Improvements in Windows, of which the following is a specification.

This invention relates to windows and sashes, particularly those of fireproof sheet-metal boxwork construction; and its objects are to improve the construction of the window-frame; to facilitate assembling the frame and sashes; to enable free access to the interior of the frame; to render the sash-guiding portions of the frame more rigid, so as to minimize liability of warping thereof and consequent binding of the sash; to provide improved means for hanging and swiveling the sashes with a view to facilitating the release of the sashes from the window-frame, so that they may swivel, particularly with a view to support either sash when swiveled at any height to which it may be raised in the window. Further objects are to improve various details, as will hereinafter appear.

In the drawings forming part of this specification, Figure 1 is a view, partly broken away, of one form of window made in accordance with my present improvements. Fig. 2 is a vertical section thereof. Fig. 3 is a horizontal sectional view taken through the upper sash and showing one form of detachable facing for the stile of the window-frame. Fig. 4 is a fragmentary sectional front view of one side of the sash, showing its trunnion, a link upon which said trunnion is hung, and a prop carried by said link for supporting the sash when swiveled. Fig. 5 is a side view of the link seen at Fig. 4. Fig. 6 shows means whereby a sash-guiding tongue is locked in normal position and may be retracted when it is desired to cant the window. Fig. 7 is a horizontal section through the stile of the window-frame, showing my preferred form of detachable facing for said stile. Fig. 8 is a fragmentary side elevation of the upper part of the stile seen in Fig. 7. Fig. 9 illustrates in dotted lines an overbalanced sash canted and supported by a prop, the normal position of the sash being shown in full lines. Fig. 10 is a bottom view of the lower bar of a sash, showing one end thereof, the other end being of like construction.

In the several views like parts are indicated by like signs.

As the parts at each side of the window may

be duplicates, only those at the left-hand side of the window are illustrated; but it will be understood that the following description applies to the parts at both sides of the window. 60

The window-frame, which is illustrated as of sheet-metal boxwork of the fireproof variety, comprises a sill 1, a head 2, and vertical stiles extending from the sill to the head. The sill and head may be of any suitable construction. Each stile consists of a back wall 3, a front wall 4, an outer side wall 5, and an inner side wall or facing 6, the whole forming a box-like structure. The walls 3, 4, and 5 are preferably formed from a single piece of metal, and the inner side wall or facing 6 preferably consists of a single piece of metal, which is detachably mounted in the window-frame. At Fig. 3 it will be seen that the back and front walls 3 and 4 are bent reflexly along their inner edges, as at 7 and 8, to form vertical grooves or recesses 9 and 10, while the vertical side edges of the facing 6 are bent at right angles to form flanges 11 and 12, which fit closely within said grooves or recesses. 75 At Fig. 7, which shows the preferred construction, the edges of the back and front walls 3 and 4 are bent toward each other, as at 13 and 14, to meet the facing 6, which is at this view narrower than the stile. 85

The walls 15 and 16 of recesses 9 are projected up through the floor 17 of the head 2, Fig. 8, to form fastening-ears 18 and 19, which are bent over upon said floor, while the flanges 11 and 12 of the facing are extended upwardly 90 to form lugs 20, which project through the floor of the head between said ears 18 and said ears 19, thereby securing said facing directly to the head and making it possible to detach the facing readily by simply swinging 95 out the lower end thereof and drawing the lugs 20 down from the head. Said facing, which, it will be seen, extends from the head to the sill, may be secured to the latter by screws 21, Fig. 7, passing through ears 22, 100 which are bent out from the bottoms of the faces and lie within vertical grooves 23 and 24, formed therein, so that by taking out the screws the facing may be readily slipped out from the stile. The interlocking of the facing-flanges 11 and 12 with the recesses formed at the edges of the stiles is of great advantage, serving to prevent the liability of loosening 105 of the facing and stiffening the entire structure. 110

The grooves 23 and 24, above referred to, receive the weight-chains 25 and 26 of the

lower and upper sashes, respectively, said chains being indicated diagrammatically at Fig. 1 and running over pulleys 27 and being connected, respectively, to counterbalancing-weights 28 and 29, which hang within the stile, as best seen at Fig. 3. Said grooves 23 and 24 are of sufficient capacity to admit trunnions 30 and 31, which project from the sashes at points somewhat above the middle of each sash, said trunnions being provided with heads 32 and 33. Between said trunnion-grooves 23 and 24 the detachable stile-facing is formed with vertical groove members 34 and 35 for receiving sash-guiding tongues 36 and 37, the latter being provided upon the sides of each sash and extending substantially the entire length thereof. Between said groove members 34 and 35 and about midway of its width said stile-facing is provided with an inwardly-projecting reflex bend forming a rib 38, which, as seen clearly at Fig. 3, divides the interior of the stile into two chambers or forms a partition between the counterbalancing-weights 28 and 29. It will be seen that when the facing is removed the rib is taken with it, thus leaving the interior of the stile entirely clear, which is a great advantage, since it renders the weights, chains, pulleys, and any other interior parts much more accessible than in prior structures. Moreover, the partition forms a stiffening-rib 38 for the facing, rendering the latter extremely rigid throughout, and since this facing serves as a guide for the sashes it will be understood its stiffness is a matter of importance, since it is desirable that the sash-guiding tongues or other guides match closely the guideways of the facing without liability of binding, which is liable to occur when the facing has not sufficient rigidity. Said stiffening-rib preferably extends the length of the facing 6. Upon each stile-facing I also preferably provide a reinforcing-plate 39, extending, preferably, for its entire length and formed at its vertical edge portions with grooves 40 and 41, which constitute linings for the groove members 34 and 35 in the facing and take the wear of the sash-guiding members 36 and 37, as seen at Figs. 3 and 7. The groove portions of these strips form stiffening-ribs, so that the strips add to the rigidity of the detachable facings, while the adjoining groove-walls 42 and 43 of the strip coöperate to form a clasp which embraces the reflexly-bent portion 38 of the facing, so as to prevent opening of said bend, the portion of the strip 39 between said walls 42 and 43 covering said reflex portion 38 of the facing.

Referring now to the sashes, each of the tongues 36 and 37 is provided with upper and lower diagonal slots 44 and 45, which engage guiding-pins 46 and 47, fixed in the sash-stiles, so that the tongues, which normally protrude from the sash-stiles, may be retracted by a diagonal movement to enable the sash to

swivel or cant. In the bottom of each sash, at each side thereof, I provide an opening 48 below each tongue, the lower end of the latter being adapted to protrude down through said opening when the tongue is retracted. Said opening is normally closed by a sliding trap 49, which is provided with a finger-hold 50, preferably in the form of a hole, and the trap is connected by a link 51 to the tongue, the pivots 52 and 53 of the link normally standing one above the other, so that the link may support or lock the tongue in normal position, as seen at Fig. 6. In register with the finger-hold 50 the floor of the lower-sash rail is provided with a long slot 54, through which the finger may be inserted to slide the trap 49 off from the opening 48 and through the link 51 to draw down the tongue. Said trunnions 30 and 31 are preferably inserted in keyhole-slots 55, formed in links 56, hung upon the chains 25 and 26, the necks of the trunnions hanging in the contracted portions of the slots and the enlarged portions of the slots being of sufficient size to permit insertion and withdrawal of the trunnion-heads, so that the sash may be readily placed in or removed from the window. Each link 56 is preferably prolonged downwardly, as at 57, and is loosely pivoted at 58 to a prop 59, said prop normally lying in the groove 23 or 24 and being adapted to swing out upon its pivot and enter any of a series of holes 60 formed in the sash-stiles, so as to support said sash at different inclinations. It will be understood that the link 56 and the prop 59 move up and down together, so as to be able to hold the sash in its canted position at any height desired with reference to the window-frame.

At Fig. 7 the front vertical molding 61 of the stile is shown as reinforced by an angle-strip extending the entire length of the molding and consisting of right-angle walls 62, 63, 64, and 65, which may be suitably attached to the contiguous stile-walls.

Variations may be resorted to within the scope of my invention, and portions of my improvements may be used without others.

Having thus described my invention, I claim—

1. A sheet-metal boxwork-stile for a window-frame, consisting of back and front walls, an outer side wall and a detachable inner side wall or facing; said facing being formed with guideways for the sashes, and between said guideways being reflexly folded to form a deep vertical partition dividing the interior of the stile into two compartments for the sash-weights; said partition forming a stiffening-rib for said facing.

2. A sheet-metal boxwork-stile for a window-frame, consisting of back and front walls, an outer side wall, and a detachable inner side wall or facing; said facing being formed with guideways for the sashes, and between said guideways being provided with a deep verti-

cal stiffening-rib which projects inwardly from said facing and is detachable therewith and divides the interior of the stile into two compartments for the sash-weights.

- 5 3. A sheet-metal boxwork-stile for a window-frame, consisting of back and front walls, an outer side wall and a detachable inner side wall or facing; said facing being formed with guideways for the sashes, and between said 10 guideways being provided with a deep vertical stiffening-rib which projects inwardly from said facing and is detachable therewith and divides the interior of the stile into two compartments for the sash-weights, said back 15 and front walls being bent along their inner edges to form grooves, and the vertical edges of said facing being bent to form flanges which fit closely within said grooves.
4. A sheet-metal boxwork-stile for a window-frame, consisting of back and front walls, an outer side wall and a detachable inner side wall or facing; said facing being formed with guideways for the sashes, and between said 25 guideways being reflexly folded to form a deep vertical partition dividing the interior of the stile into two compartments for the sash-weights; said facing being narrower than the stile, and the inner edges of the back and front walls being bent toward each other to meet 30 said facing, and also having formed therein vertical grooves, and the vertical edges of said facing being bent to form flanges which fit closely within said grooves.

5. A sheet-metal boxwork window-frame 35 comprising a pair of stiles, a sill and a head; each stile consisting of back and front walls, an outer side wall, and a detachable inner side wall or facing having guideways for the sashes; said back and front walls being bent 40 along their inner edges to form grooves, and the walls forming the sides of said grooves being projected through the floor of the head to form fastening-ears which are bent over upon said floor; and the vertical edges of said 45 facing being bent to form flanges which fit closely within said grooves and also are extended upwardly to form locking-lugs which project through the floor of the head between said ears.

- 50 6. A sheet-metal window-frame comprising a pair of stiles, a sill and a head; each stile consisting of back and front walls, an outer side wall, and a detachable inner side wall or facing having guiding-grooves for the sashes; 55 said back and front walls being bent along their inner edges to form grooves, the walls forming the sides of said grooves being projected through the floor of the head to form fastening-ears which are bent over upon said 60 floor, and the vertical edges of said facing being bent to form flanges which fit closely within said grooves and also are extended upwardly to form locking-lugs which project through the floor of the head between said 65 ears, and ears bent out from the bottoms of the

facings within said grooves and secured to the sill.

7. In a window-frame, a detachable stile-facing extending in one piece from sill to head and provided with sash-guiding grooves and 70 having between said grooves a stiffening-rib which projects inwardly from said facing and is detachable therewith and forms a partition for separating the sash-weights.

8. In a window-frame, a detachable stile-facing extending in one piece from sill to head and provided with sash-guiding ways and having between said ways a vertical reflex bend forming an integral stiffening-rib which serves 75 as a partition for separating the sash-weights. 80

9. In a window-frame, a detachable stile-facing extending in one piece from sill to head and provided with sash-guiding grooves and having between said grooves a vertical reflex bend forming an integral stiffening-rib which 85 serves as a partition for separating the sash-weights, said facing having a locking projection at the top, and also having at the bottom an outwardly - bent ear within one of said grooves for securing to the sill. 90

10. A boxwork window-frame comprising a pair of stiles, a sill and a head; each stile comprising two pieces of metal, whereof one forms three sides of the stile and is permanently joined to the sill and head, and the other is detachably mounted in position to form the inner side or facing of the stile, and is provided with sash-guiding ways, said two stile-pieces interlocking with each other at their edges in such a manner that said facing 100 may be detached, the edges of said three-sided piece being reflexly folded to form recesses, the edges of said detachable facing being bent inwardly to form flanges which fit closely within said recesses, and said facing being 105 formed between said sash-guiding ways with an integral reflex inwardly - projecting rib which forms a partition for separating the sash-weights. 110

11. In a boxwork sheet-metal window-frame, a detachable sash-guiding stile - facing plate formed with two pairs of vertical grooves and also formed between said pairs with an integral reflex rib for projecting into the interior of the stile and serving as a partition 115 to separate the sash-weights.

12. In a boxwork sheet-metal window-frame, a detachable sash-guiding stile - facing provided with a midway vertical inwardly-projecting stiffening-rib which extends for substantially the entire length of the facing and is detachable therewith. 120

13. A boxwork sheet-metal window-frame comprising a detachable stile-facing which is formed with sash-guiding grooves and is also 125 provided with reinforcing - plates within the grooves.

14. A boxwork sheet-metal window-frame comprising a stile-facing which is formed with sash-guiding grooves and is also reflexly 130

bent between said grooves to form a stiffening-rib which projects within the stile and forms a partition for separating the sash-weights, and a reinforcing-plate covering said 5 reflex bend, and formed with grooves which line the grooves in said facing and take the wear of the sash-guiding members.

15. A boxwork sheet-metal window-frame each of whose stiles has formed therein a plurality of sash-guiding grooves, and a reinforcing-strip for each of said stiles, said strip being provided with a plurality of grooved portions which fit within said grooves to take the wear of the sashes.

15 16. In a boxwork sheet-metal window-frame, a detachable sash-guiding stile-facing provided with a midway vertical inwardly-projecting stiffening-rib extending for substantially the entire length of the facing; said facing reaching from sill to head and having means for attachment to both sill and head.

17. The combination with a window-frame, of a sash therein; said sash being provided at each side with a guiding-tongue and a flexible 25 connection side by side; and said window-frame being provided at each side with a pair of grooves side by side, one for said tongue and one for said flexible connections; and a counterbalance connected to said flexible connection.

18. The combination with a window-frame, of a sash therein; said sash being provided at each side with a releasable guiding-tongue and a flexible connection side by side, and being 35 also provided with trunnions whereby it is hung upon its flexible connections; and said window-frame being provided at each side with a pair of grooves side by side, one for the tongue and one for the trunnion and its 40 connection; and counterbalancing means connected to the flexible connections.

19. The combination with a window-frame of two sashes therein; said sashes being each provided at each side with a releasable guiding-tongue and a flexible connection side by side, and each sash being also provided with trunnions whereby it is hung upon its flexible 45 connections; said window-frame comprising a sill, a head and a pair of stiles, each of the 50 latter having two pairs of grooves, one groove in each pair to receive the sash-tongue, and one groove in each pair to receive the trunnion; and counterbalancing means connected to said flexible connections.

55 20. The combination with a window-frame of two sashes therein; said sashes being each provided at each side with a releasable guiding-tongue and a flexible connection by the side thereof, and each sash being also provided with trunnions whereby it is hung upon its flexible connections; and said window-frame comprising a sill, a head and a pair of stiles, each of the latter having a detachable facing provided with two pairs of grooves, 60 one groove in each pair to receive the sash-

tongue, and one groove in each pair to receive the trunnion and counterbalancing means connected to said flexible connections.

21. A sheet-metal boxwork-sash provided upon its side with an upright guiding-tongue 70 which is mounted for diagonal movement, the bottom bar of the sash being provided with an opening beneath said tongue, and a trap closing said opening and operatively connected to said tongue.

75 22. A sheet-metal boxwork-sash provided upon its side with an upright guiding-tongue which is mounted for lateral movement, a sliding member mounted upon one of the top and bottom bars of the sash, and a link connecting 80 said sliding member to said tongue.

23. A sheet-metal boxwork-sash provided upon its side with an upright guiding-tongue which is mounted for diagonal movement, a sliding member mounted upon one of the top 85 and bottom bars of the sash, and a link connecting said sliding member to said tongue, and normally locking the latter in its protruded position.

24. A sheet-metal boxwork-sash provided 90 upon its side with an upright normally protruding guiding-tongue which is mounted for diagonal movement, the bottom bar of said sash being provided with an opening, a sliding trap for closing said opening, and a link 95 connecting said trap to said tongue.

25. A sheet-metal boxwork-sash provided upon its side with an upright normally protruding guiding-tongue which is mounted for diagonal movement, the bottom bar of said 100 sash being provided with an opening, a trap for closing said opening, and a link connecting said trap to said tongue; said opening being beneath the tongue, and the latter being retractable by the opening movement of the 105 trap and adapted to protrude at its lower end through said opening.

26. A sheet-metal boxwork-sash provided upon its side with an upright guiding-tongue which is mounted for diagonal movement, the 110 bottom bar of said sash being provided with an opening, a sliding trap for closing said opening, and a link connecting said trap to said tongue; said opening being beneath the tongue, and the latter being retractable by 115 the opening movement of the trap and protruding at its lower end through said opening, and said link standing upright when the trap is closed and locking the tongue in its normal position.

120 27. A sheet-metal boxwork-sash provided upon its side with an upright normally protruding guiding-tongue which is mounted for diagonal movement, the lower bar of the sash being provided with an opening through 125 which the lower end of the tongue may project when it is retracted, and a trap which closes said opening and locks said tongue in its normal position.

28. A sheet-metal boxwork-sash provided 130

upon its side with an upright normally protruding guiding-tongue which is mounted for diagonal movement, the lower bar of the sash being provided with an opening through which the lower end of the tongue may project when it is retracted, and a trap for closing said opening and locking said tongue in its normal position; said trap being provided with a finger-hold, and said lower bar being provided with a long slot registering with said hold.

29. The combination with a pair of sash-chains, counterbalancing - weights attached thereto, and pulleys over which said chains run, of a sash and sash-prop both supported by said chains; said sash being swiveled at its points of connection to said chains, and being provided with retractable guiding - tongues, and said prop being capable of supporting the sash in an inclined position.

30. The combination with a sash, of a pair of counterbalancing-weights, a pair of flexible connections, pulleys for said connections, trunnions for said sash, a link attached to one of said connections and having a bearing for one of said trunnions, a prop pivoted to said link, and means for supporting the other of said trunnions upon the other of said flexible connections.

31. The combination with a sash, of a pair of counterbalancing-weights, a pair of flexible connections, pulleys for said connections, trunnions for said sash, a link attached to one of said connections and having a bearing for one of said trunnions, said trunnion comprising a neck and a head, and said link having a keyhole-slot in which said neck has a bearing, a prop pivoted to said link, and means for supporting the other of said trunnions upon the other of said flexible connections.

32. The combination with a sash, of a pair of counterbalancing-weights, a pair of flexible connections, pulleys for said connections, trunnions for said sash, a link attached to one

of said connections and having a bearing for one of said trunnions, a prop pivoted to said link and depending below said trunnion, and means for supporting the other of said trunnions upon the other of said flexible connections.

33. The combination with a sash, of a pair of counterbalancing-weights, a pair of flexible connections, pulleys for said connections, trunnions for said sash, a link attached to one of said connections and having a bearing for one of said trunnions, a prop pivoted to said link and depending below said trunnion, a series of holes in the adjoining stile of the sash, into any of which the tip of said prop is adapted to be inserted, and means for supporting the other of said trunnions upon the other of said flexible connections.

34. A sheet-metal boxwork-sash provided upon each side with an upright guiding-tongue which is mounted for diagonal movement, the bottom bar of said sash being provided upon its under side with openings, one beneath each tongue, traps for closing said openings, and operative connections between said traps and said tongues.

35. In a sheet-metal window, a jamb the facing of which is formed of a piece of sheet metal bent to form runways, and the edges of which are projected laterally; lateral folds along the edges of the sheet metal which form the remainder of the jamb within which the laterally-projecting edges of the facing-piece are received; an opening whereby one end of said facing is received and held within the frame; and screws whereby the other end of the facing is detachably secured to the frame, substantially as described.

Signed at Nos. 9 to 15 Murray street, New York, N. Y., this 29th day of June, 1903.

HENRY C. SMITH.
